UNITED STATES PATENT OFFICE.

WALTHER NERNST, OF GÖTTINGEN, GERMANY, ASSIGNOR TO NERNST LAMP COMPANY, OF PITTSBURGH, PENNSYLVANIA, A CORPORATION OF PENNSYLVANIA.

ELECTRIC GLOW-LAMP.

1,106,961.

Specification of Letters Patent. Patented Aug. 11, 1914.

Original application filed March 29, 1898, Serial No. 675,603. Divided and application filed December 18, 1906, Serial No. 348,567. Divided and this application filed April 24, 1913. Serial No. 763,184.

To all whom it may concern:

Be it known that I, WALTHER NERNST, a subject of the German Emperor, and resident of Göttingen, in the Kingdom of Prussia, German Empire, have invented certain new and useful Improvements in Electric Glow-Lamps, of which the following is a specification.

My invention relates to the class of electric lamps in which the light emitting element or member is a non-conductor at ordinary temperatures and which may be made conductive by subjecting it to a relatively high degree of heat.

15 The object of my invention is to provide a light emitting member or glower of such composition of materials as shall specially adapt it for efficient service and long life.

20 I have found that a glower formed of a mixture of certain materials will become conductive at a lower temperature and be more durable in service than a glower made of a single material, provided the materials 25 are thoroughly powdered and mixed together, then combined with a suitable binding material, and formed into the proper shape and thoroughly baked, suitable terminals of conducting material being attached to the ends of the glower in order 30 to facilitate connecting it in circuit for operation.

My invention contemplates the employment of any one of a considerable variety 35 of mixtures of materials, but mixtures of two or more of the oxids of zirconium, yttrium, thorium, beryllium, and magnesium will generally be found most desirable. I may, however, combine one of these ox- 40 ids, such, for example, as the oxid of magnesium, with a small percentage of boric acid, chlorid of calcium, tungstic acid, or the like.

When a glower formed of a proper mixture of two or more of the materials above 45 specified is connected in an electric circuit

and heated to its conducting temperature, the heat developed in itself by the passage of a current therethrough will serve to maintain it in a conducting condition and cause it to yield light in a very efficient 50 manner.

As an illustration of my invention, I show, in the accompanying drawing, a glower 1 which is a non-conductor at ordinary temperature. As a simple means for 55 raising the glower to conducting temperatures, I show a torch 2 supported upon a suitable base 3.

It is to be understood that the illustration is in no sense restrictive, as regards either 60 the form or dimensions of the glower or the means employed for heating it to conducting temperature.

This application is a division of my application filed December 19th, 1906, Serial 65 Number 348,567, issued as Patent, Number 1,071,649, August 26, 1913, which is a division of my application March 29th, 1898, Serial Number 675,603, issued October 6th, 1908, as Patent 900,416 and another division 70 thereof is application filed September 10th, 1908, Serial Number 452,485.

I claim as my invention:

1. A homogeneous conductor for electric lamps containing intimately mixed calcium 75 and tungsten in the form of compounds.
2. A light giving body for electric lamps, comprising intimately mixed tungsten, calcium and oxygen.
3. A radiant body comprising intimately 80 mixed calcium and a metal and oxygen.
4. An illuminant for electric lighting comprising intimately mixed the oxids of calcium and tungsten.

Signed at Berlin, Germany this 17 day 85 of March, A. D. 1913.

WALTHER NERNST.
